UNITED STATES PATENT OFFICE.

JAMES G. HANES, OF WINSTON-SALEM, NORTH CAROLINA.

APPARATUS FOR DRYING HOSIERY.

Application filed March 14, 1922. Serial No. 543,730.

To all whom it may concern.

Be it known that I, JAMES GORDON HANES, a citizen of the United States, residing at Winston-Salem, county of Forsyth, State of North Carolina, have invented certain new and useful Improvements in Apparatus for Drying Hosiery, of which the following is a specification, reference being had to the accompanying drawings.

10 This invention relates to hosiery drying apparatus and more particularly to drying forms or boards over which the moist hosiery is drawn so as to give form to the hose while the latter is dried, by the application 15 of heat, in any suitable manner.

An object of the invention is to provide a novel clamping means to engage and press the hose tightly against the sides of the form during the act of drying, whereby to prevent shrinkage of any portion or creeping 20 of the garment lengthwise of the form, said clamping means embodying preferably, a foot operated arrangement to throw or release the clamping means at will while leaving the hands free to adjust or strip the garment to or from the form, a self-locking device to hold the clamping means in clamping position, and a releasing means operable 25 independently of the foot operated arrangement.

In addition to the foregoing this invention comprehends improvements in the details of construction and arrangement of the correlated parts of what is now considered to be 30 the preferred form of the invention from among other possible forms and arrangements devisable within the spirit of the invention and the scope of the appended claims.

40 In the accompanying drawings:

Fig. I is a view in side elevation of a hosiery drying form and clamping means constructed in accordance with the present invention and illustrating the clamping means 45 in open position.

Fig. II is a similar view showing the relation of the parts when the clamping members are in clamped position; and

50 Fig. III is a view of the apparatus in front elevation.

With reference to the drawings 10 indicates a horizontal support which may be in the form of a pipe, rod or the like and adapted to support one or more drying forms, one of which is indicated at 11 and formed with a foot 12 which rests upon or

is secured to the support 10. Said foot is flanked at either side by means of a split bearing block 13 each consisting of two complementary parts having their adjacent faces recessed to receive the support between them, the parts being subsequently held together by means of bolts 14 which enter aligned openings formed in flanges thereof so as to fix the bearing blocks immovably upon the support. Extending through openings in the bearing blocks are a pair of horizontal rods 15, one located at each side of the support 10, and fixedly mounted on each rod, between each pair of bearing blocks is a clamping arm 16 adapted for movement toward and away from the drying form. Associated with each of said clamping arms is an operating lever 17, preferably of a laminated construction and comprising a pair of plates 18, perforated so as to be loosely fulcrumed upon the rod 15 and connected at their upper ends by means of a block 19 interposed therebetween. The adjacent faces of each block 19 and its associated arm 16 are recessed to receive the ends of a spring 20 which functions to urge the clamping arm toward the form independently of its operating lever 17. The upper ends of the levers 17 are normally urged apart to permit ready release of the clamping arms, by means of a spring 21 which connects the lower ends of said levers. To limit outward movement of the upper ends of the levers a pair of U-shaped clips 22 are provided, each located behind one of the said levers and pivotally supported at their ends upon the bearing blocks 13. The lower ends of the plates 18 forming the operating levers are beveled outwardly to form contacting faces 23 for engagement with a spreader cam 24 having a pair of beveled surfaces 25 and parallel sides 26. These cam surfaces may be reinforced by covering the same with a conformable wearing plate 27. The contacting faces 23 of the levers may be prolonged by interposing blocks 28 between the plates forming the levers and releasably securing said blocks in place by means of screws 29. The cam is raised and lowered axially by means of a lever 30 pivoted at one end to the lower end of an extension 31 of said cam, said lever being fulcrumed upon a suitable support 32 and formed at its opposite end with a tread portion 33. The upper end of each arm 16 is provided with a clamping pad 34, each consisting of a pair

of plates 35, curved to conform to the shape of the drying form and held together by means of bolts 36. The outer face of the innermost plate of each pad is covered with a sheet of fine mesh wire fabric or the like 37, the edges of which are caught between the plates prior to the tightening of the bolts 36. The outermost plate of each pair is provided with a pair of bolts 38 which enter openings formed in the arm 16, said openings being enlarged to receive springs 39 which embrace the bolts and act to urge the pads outward within the limit of movement of the pads relative to their supporting arms, the limit being determined by the engagement of nuts 40 (one of which is applied to the protruding end of each bolt 38) against the side of the arm.

In operation, the garment is drawn over the form and smoothed to erase any wrinkles and finally the lever 30 is depressed by means of the foot which results in the upward movement of the cam 24. The point of the cam, upon entering the space between the bevelled faces 23 and upon continued movement causes the lower ends of the levers 17 to separate and the arms 16 to move toward the form, motion of said levers being transmitted through the springs 20 to said arms. The pads 34 are thus brought into contact with the selvage or leg end of the garment. Upward movement of the cam is continued until the straight sides 26 are brought between the levers, and the parts assume the position shown in Fig. II, comparison of which with Fig. I will disclose the fact that both the springs 20 and 39 are under strain, the combined tension thereof urging the pads resiliently but tightly against the garment, which may now be dried without shrinking or creeping of the same along the form. The cam thus constitutes a locking element which effectively retains the arms in clamped position. Drying may be effected in various ways well known in this art, as for instance, by introducing live steam to the interior of the form which is made hollow for this purpose, the hollow support 10 serving as a conduit, or by heating the form electrically. The structure described constitutes a unit of a series of such devices which may be arranged in groups of six or twelve. Thus, the rods 15 are of such a length as to span or include six or twelve of the units within their lengths; and, it will be obvious that after the garments of a group are dried said garments may be quickly released, by rotating the rods 15, the motion of which is transmitted to all the clamping arms 16 of said group, thereby causing said arms to move simultaneously away from the forms 11 against the tension of the springs 20. The release of the arms is thus accomplished independently of the foot levers, the latter being sub-

sequently returned to normal position. Owing to the mounting of the pads upon the arms through the medium of the loosely fitting bolts 38, a limited amount of universal motion of the pads is permitted which enables the pads to more readily adjust themselves to the shape of the form. The function of the wire fabric covering of the pads is to ensure a firm grip on the garment and to permit the escape of moisture throughout the area of contact of the pad. The plates forming the pad structure are perforated to facilitate this action. Obviously, the cam 24 may be operated in any other manner than by depression of the foot, as for instance by substituting a movable element against which the operator leans his body or operates by hand.

Having thus described my invention, I claim:

1. In a garment drier, a form over which the garment is stretched, means to clamp the garment against the form, foot operated means to move the clamping means to garment engaging position, and means adapted for manual operation to move the clamping means out of garment engaging position independently of the foot operated means.

2. In a garment drier, a form over which the garment is stretched, clamping means to engage the garment against the form, means to move said means to garment engaging position and to simultaneously lock the moving means against movement, and means operable independently of the moving means to move said clamping means out of clamping position while the first moving means is in locked position.

3. In a garment drier, a form over which the garment is stretched, clamping means movable toward and away from the form, and garment engaging pads carried by said clamping means and mounted thereon for movement toward and away from said clamping means to engage the garment and press the same against the form.

4. In a garment drier, a form over which the garment is stretched, clamping means movable toward and away from the form, pads to engage the garment against the form, pins supporting the pads and guided for movement in the clamping means toward and away from said clamping means, and resilient means carried by said clamping means to urge the pads toward garment engaging position.

5. In a garment drier, a form over which the garment is stretched, clamping means to engage the garment against the form, operating means to shift the clamping means toward and away from the form and a resilient connection between the clamping and operating means whereby motion from the operating to the clamping means is transmitted through said resilient connection.

6. In a garment drier, a form over which the garment is stretched, clamping arms movable toward and away from the form, an operating lever for each arm, and a resilient connection between each lever and its associated arm whereby said arms may be released from engagement with the form independently of and in any position of the levers.
- 10 7. In a garment drier, a form over which the garment is stretched, clamping members to engage the garment against the form, a pair of levers to operate said clamping members, and a cam member adapted to penetrate between and to shift the levers simul-
- taneously to actuate said clamping members.
8. In a garment drier, a form, pivoted clamping structures, and means to enter between the structures at one end thereof to separate said ends and thereby move the opposite ends into clamping engagement with the form. ²⁰

In testimony whereof I have hereunto signed my name at Philadelphia, Pennsylvania, this eighth day of March, 1922.

JAMES G. HANES.
